(57) **CLAIM**

I claim the ornamental design for an outsole for a shoe, as shown and described.

DESCRIPTION

FIG. 1 is a bottom plan view of an outsole for a shoe showing my new design;

FIG. 2 is a left side view thereof;

FIG. 3 is a right side view thereof;

FIG. 4 is a front view thereof;

FIG. 5 is a rear view thereof;

FIG. 6 is an enlarged perspective view of the area labeled “6” in FIG. 1; and,

FIG. 7 is an enlarged perspective view of the area labeled as “7” in FIG. 6; the pyramidal shapes being understood to extend across the surfaces of each raised tread and hexagonal shape on the outsole.

The broken line forming a closed curved shape in the arch area of FIG. 1, along with the parallel broken lines around the periphery in FIGS. 2–6 represent the internal boundaries of the design, with the lines themselves and the areas within them, forming no part of the claim.
